DIGITAL READOUT SLIDE CALIPER

Kenju Uchino, Utsunomiya, Japan, assignor to Yehan
Numata, Yokohama City, Kanagawa Prefecture, Japan

Filed Mar. 29, 1973, Ser. No. 346,189

Term of patent 14 years

Int. Cl. D10—04

U.S. Cl. D52—6 B

FIG. 1

FIG. 2

FIG. 3

FIG. 4

FIG. 5

FIG. 6

FIG. 7

FIG. 1 is a front elevational view of a digital readout slide caliper showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a front perspective view thereof.

I claim:

The ornamental design for a digital readout slide caliper, as shown.
